ATTORNEY

UNITED STATES PATENT OFFICE.

JAMES MUNDELL, OF PHILADELPHIA, PENNSYLVANIA.

DESIGN FOR A GONG-STRIKER CAP.

SPECIFICATION forming part of Design No. 25,881, dated August 4, 1896.

Application filed June 20, 1896. Serial No. 596,345. Term of patent 8½ years.

To all whom it may concern:

Be it known that I, JAMES MUNDELL, a citizen of the United States, residing at the city and county of Philadelphia, State of Pennsylvania, have invented and produced a new and original Design for Gong-Striker Caps, of which the following is a specification.

In the drawings forming part of this specification, Figure 1 is a side elevation; Fig. 2, a plan view; Fig. 3, a sectional elevation, and Fig. 4 a bottom view.

The essential feature of the design consists in the configuration, substantially as herein shown and described.

The cap consists of a dish-shaped body, circular in plan, as shown in Fig. 2, comprising a curved crown 1, an annular flange 2, de-

pending from the edges of the crown, and an annular and inwardly-extending flange 3, in the center of which is formed a circular hole 4. On the top of the crown is disposed a series of conical teats 5, arranged near the center of the crown and concentric with the periphery thereof.

Having described my invention, I claim—

The design for a gong-striker cap, substantially as herein shown and described.

Signed at the city and county of Philadelphia, State of Pennsylvania, this 15th day of June, 1896.

JAMES MUNDELL.
